WINDOW CONSTRUCTION

George C. Hayman, Wheatridge, and Charles M. Shepherd, Jr., Boulder, Colo.; said Shepherd, Jr., assignor to said Hayman.

Application February 12, 1951, Serial No. 210,486

10

11 Claims. (Cl. 20—54)

This invention relates to windows, and more particularly to sash windows.

For many years, the customary construction of windows has included a rectangular wooden framework in which upper and lower sashes are movable vertically, the sides of the sashes riding in channels formed by vertically extending strips, attached to the side members or jambs of the frame. Generally, the entire side edge of the sash rides in the channel, so that oftentimes the friction to be overcome in raising or lowering a window requires a much greater force to be exerted than mere lifting of the weight of the sash. Also, the sashes for such windows comprise a wooden framework, surrounding a pane of glass, while to balance the weight of the sashes, and to hold the sashes suspended in a desired position, a sash cord is attached to each side of each sash frame, such cords extending over pulleys at the top of the window frame and then to weights, enclosed and movable within a hollow vertical space formed by and at each side of the frame. Such construction is comparatively expensive, due not only to the cost of mounting the sash weight pulleys in mortised holes, but also the additional time required by workmen in installing the sash cords and weights, as well as completing the frame boxes to provide enclosed spaces for the weights. In addition, such previous types of sash windows are difficult to clean, since access to the outside of the pane (except by a person physically positioned outside the window) can be obtained only by moving the lower sash up, to reach the outside of the upper sash pane, and by moving the lower sash partly up to reach the lower half of the lower sash pane, and then moving the upper sash completely down and positioning the lower sash near the top of the window, to reach the upper half of the lower sash pane. Thus, the outside of the pane of the lower sash is reached with considerable difficulty from a position inside the window.

Among the objects of the present invention are to provide a novel window construction of the sash type; to provide such a window construction in which the window sashes are adequately guided and are adequately sealed against the leakage of air around the sash edges; to provide such a window construction in which the sashes may be maintained in any desired position, without the necessity of sash weights or the like; to provide such a window construction in which the sashes are readily removable from the window frame for cleaning or other purposes; to provide such a window construction in which a variation in the ventilating positions of the sashes may be obtained; to provide novel side frame elements, particularly adapted to guide and also to seal the edges of window sash; and to provide such a window construction and side frame elements which are relatively simple in construction and economical to manufacture.

Additional objects and the novel features of this invention will become apparent from the following description, taken in connection with the accompanying drawings, in which:

2

Fig. 1 is a vertical section taken centrally through a window construction of this invention;

Fig. 2 is a fragmentary, three-dimensional view, taken at one side of the central portion of the window construction of Fig. 1;

Fig. 3 is a fragmentary, three-dimensional view of a side frame guiding and sealing element, constructed in accordance with this invention and also shown in Fig. 2;

Figs. 4 and 5 are fragmentary, three-dimensional views, similar to Fig. 3, of alternative side frame guiding and sealing elements;

Fig. 6 is a fragmentary, three-dimensional view illustrating a further alternative side frame element construction, wherein metal parts are reduced to a minimum;

Fig. 7 is an enlarged fragmentary sectional perspective view taken along line 7—7 of Fig. 6;

Fig. 8 is an enlarged fragmentary sectional perspective view, taken at the lower end of the lower sash of Fig. 1;

Fig. 9 is a fragmentary, cut-away perspective view illustrating a sash holding device as installed in a window sash, and exemplifying one type of holding device adapted to cooperate with the side frame element shown in Fig. 4;

Fig. 10 is an enlarged side elevation of the holding device of Fig. 9, certain parts being cut away to illustrate the interior construction, the holding device being in a sash guiding and retaining position;

Fig. 11 is a similar side elevation of the holding device, with certain parts cut away to show the interior construction, the holding device being in a sash removal position;

Fig. 12 is an exploded perspective view of the parts of the holding device of Figs. 9—11;

Fig. 13 is a plan view of a blank from which a shoe holder, one of the parts of Fig. 12, may be made;

Fig. 14 is a fragmentary, three-dimensional view illustrating an additional alternative side frame element construction;

Fig. 15 is a cross section taken along line 15—15 of Fig. 16;

Fig. 16 is a longitudinal section taken along line 16—16 of Fig. 15;

Fig. 17 is a fragmentary, exploded three-dimensional view of a further alternative side frame construction; and

Fig. 18 is a fragmentary enlargement of the central portion of Fig. 17, in assembled position.

A window construction of this invention, as illustrated in Figs. 1 and 2, may be applied to a frame F having therein a longitudinally movable upper sash U and lower sash L, each side or jamb 10 of the frame being provided with a guiding and sealing track T and each sash being provided with at least one holding device H, the tracks T being constructed in accordance with this invention and the holding device H constructed as illustrated in Figs. 9—13, inclusive, or in accordance with my U. S. Patent No. 2,521,292, or in any other suitable manner. In general, the track T provides a groove or equivalent means for guiding the edges of the sashes upwardly and downwardly, while the holding device H permits either sash to be removed from the frame, and also permits one of the sashes, such as the lower sash L, to be tipped outwardly, such as against a stop pin 11, to the full position of Fig. 1, for ventilation without a direct current of air flowing through the window, as when the lower sash is raised or the upper sash lowered. A stop pin 11 is preferably provided on each jamb 10, so that when the lower sash L is tipped with its lower end resting on the sill 12 of the frame, an aperture 13 will be provided between the sashes. As will be evident, air passing through the aperture 13 is deflected upwardly by the lower sash, so that a direct air current against a person in the room thereby tends to be avoided.

The lower sash L may be provided with a holding device H and a guide pin 14 on each side. The holding

device H includes a shoe 15, made of plastic or the like and shown more clearly in Figs. 9, 10 and 12, which rides in a groove 16, shown in Fig. 2, of the track T, while the guide pins 14 extend laterally from a lower bar 17 of the frame of the lower sash L and also ride in groove 16. In the dotted position of Fig. 1, the lower sash L may be moved upwardly and downwardly, as described later. The upper sash may be provided with a single holding device H, since it abuts against a blind stop 18, but a guide pin 19 extends laterally at each side from the lower bar 20 of the upper sash U. Both the guide pins 19 and the shoe 15 of the holding device H of the upper sash U ride in a second longitudinally extending groove 21 of the track T.

The track T may be constructed in the manner shown in any of Figs. 3-6, inclusive, or in any of Figs. 14-17, inclusive. As illustrated in Figs. 2 and 3, the track may comprise two flexible metal strips, rolled or drawn to the desired shape, the strips being made out of a sufficiently resilient material that pressure will tend to be exerted against the edge of the side bars 22 and 23 of the upper and lower sashes, respectively. The strips are preferably sufficiently thin that they will tend to flex when unsupported for a predetermined distance, but are considerably less flexible when supported over a span of a shorter distance. In addition to the groove 21, one track strip may be provided with a section disposed centrally of the jamb 10 and having two oppositely inclined portions 24 and 24', forming a dihedral angle therebetween of slightly less than 180°, such as approximately 160°, i. e. each of the portions 24 and 24' may extend at an angle of approximately 10° with respect to a line parallel to the surface of jamb 10. Adjacent the portions 24 and 24', and on opposite sides thereof, additional portions 25 and 25' may extend outwardly and at an angle of approximately 45° to the surface of jamb 10, the outer edge of portion 25 being connected by a flat or land 26 with an inverted arcuate section forming the groove 21. A flat or land 27, on the outside of groove 21, is connected to an arcuate section 28, while the second strip of the track of Fig. 3 includes an inner flat or land 29, disposed beneath the 45° portion 25' and connected to an inverted arcuate section forming groove 16, in turn connected by a land 30 with an arcuate section 31, similar to arcuate section 28. All of the foregoing portions of the strips, of course, extend longitudinally of the jamb 10, and the strips are preferably uniform in cross-sectional shape along their lengths. The arcuate sections 28 and 31 extend from the surface of jamb 10 to engage the surface of the side bars 22 and 23, respectively, of the sashes, in a less flexible manner than the central portions 24 and 24'. To accommodate the arcuate sections forming grooves 16 and 21, respectively, the jamb 10 may be provided with milled grooves 32 and 33, which are not necessarily rectangular in cross section, although the same is readily produced. The metal strips of the track may be attached to the jamb in any suitable manner, as by a longitudinal series of nails through land 26 of one strip and land 29 of the other strip, as shown, so that when a sash presses against a central inclined portion 24 or 24', the outer edge of portion 25' may move laterally along land 29. As will be evident, the engagement of the side bar of a sash with one of the central portions 24 or 24' provides a resilient seal, acting to prevent the flow of air around the edges of the sash, while the less flexible engagement of the arcuate sections 28 and 31 provides a relatively steady supporting and aligning surface for the sash. In order further to seal the sashes, when closed, against the possible entrance of air around the upper and lower edges of each sash, weather stripping 34 may be installed to extend laterally across the bottom of the lower bar 17 and along the top bar 35 of the lower sash L, and also across the top edge of the top bar 36 of the upper sash U, as in Fig. 1.

In the alternative construction of the track T shown

in Fig. 4, a single metal strip is utilized, rather than two strips. Such a strip includes inverted arcuate sections forming the grooves 16 and 21, both of the arcuate sections 28 and 31, the central portions 24 and 24', and 5 the adjacent portions 25 and 25'. As before, the arcuate sections forming grooves 16 and 21 are connected by lands 30 and 27, respectively, with arcuate sections 31 and 28, but the inverted arcuate section forming groove 16 is connected by a flat or land 37 with inclined portion 10 25'. Also, the milled grooves 32' and 33' are preferably wider than the milled grooves 32 and 33 of Fig. 3, being preferably sufficiently wider than the arcuate sections forming grooves 16 and 21, to accommodate lateral movement of the latter, produced by pressure of a sash 15 against a central portion 24 or 24', pushing the same inwardly toward the jamb 10. The track of Fig. 4 may be attached to the jamb in a suitable manner, as by a series of 20 nails driven through the central point of the metal strip and into the jamb. As will be evident, the central portion 20 of the strip may work in and out, as it were, on the nails, which will of course extend above the metal strip when the latter is compressed. However, as will be evident from Figs. 1 and 2, the side bars 22 and 23 of the upper and lower sashes, respectively, are spaced laterally 25 from each other, so that neither side bar tends to strike the nails when passing along the strip. Also, the slight inclination of the central portions 24 and 24' tends to throw each of the sashes away from center, although undue movement in that direction is prevented by the 30 positioning of the shoes of the holders H and the respective guide pins 14 and 19 in the respective grooves 16 and 21.

In the alternative construction of Fig. 5, the inverted arcuate sections providing grooves 16 and 21 are joined 35 by a flat or land 38, extending across the surface of jamb 10, between milled grooves 32 and 33, thereby forming a first strip in which are also formed the lands 27 and 30 and the arcuate sections 28 and 31. A second strip may include the slightly inclined central portions 24 and 24', 40 and the opposed, more inclined portions 25 and 25', which may move laterally along land 38. The first strip may be attached to the jamb in any suitable manner, as by nails through the flat 38, while the second or central strip may be attached by nails in spaced positions along the 45 center ridge between inclined portions 24 and 24'.

As in Fig. 2, each holding device H may be mortised into the side bar 22 or 23 of the respective sash, while the shoe 15, of Figs. 9-11, is adapted to be withdrawn from the extending position of Fig. 10 to the retracted position 50 of Fig. 11, by manual operation of a handle 40, such as on the holding device of the lower sash, or a coin or similarly operating simple instrument, inserted in a slotted pin or handle 41 of the holding device H for the upper sash. Generally speaking, the handle 40 of each holding device 55 for the lower sash is preferably manually operated, since during general use, the lower sash may be swung outwardly to the full position of Fig. 1, in which the lower sash rests against the stop pins 11, since for this operation it is necessary only to grasp the handles 40 of the holding devices on 60 each side of the lower sash and pivot them inwardly, thereby withdrawing the respective shoes 15 and permitting the lower sash to be pulled to the stop position. Otherwise, during use each sash is merely slid upwardly or downwardly to a desired position. However, when it is 65 desired to remove a sash from the frame, as for cleaning purposes and the like, the lower sash may be slid upwardly until the lower bar 17 thereof is at or above the position of stop pins 11, whereupon the handles 40 may be pivoted inwardly, and the upper portion of the sash pulled out from 70 the frame, as to a generally horizontal position. In such position, one edge of the lower sash may be tilted, so that the guide pin 14, on that side, will clear the track, and the lower sash may be removed from the frame F. For removal of the upper sash from the frame, it is necessary 75 only to lower it slightly until the top bar 36 can be

grasped with one hand, whereupon a coin or other simple instrument, operating on the principle of a screw driver, may be inserted in the slotted handle 41 of the holding device, and upon retraction of the shoe 15 to the position of Fig. 11, the top of the upper sash may be pulled outwardly from the frame, and the sash moved down to a substantially horizontal position. In this position, as in the case of the lower sash, one edge may be tipped until the guide pin 19 on that side clears the track T, whereupon the sash may be removed from the frame. As will be evident, the handle 41 of the holding device for the upper sash is used considerably less frequently than the handle 40 for the lower sash, and therefore may be actuated in the manner indicated, but it will be understood that the handle for the holding device for the upper sash may be manually operated, in substantially the same manner as the holding device handle for the lower sash, and vice versa.

In the alternative track construction illustrated in Figs. 6 and 7, the use of metal is avoided as far as possible, the resiliency of the track being produced by a strip 43 of resilient non-metallic material, such as foam rubber or the like, placed in a groove 44 milled in a jamb 10', and providing a resilient backing for a non-metallic strip 45 of non-resilient material, such as wood, against which the corners of the side bars 22' and 23' of the upper and lower sashes, respectively, are adapted to bear, the corners being provided with right angle grooves 46, adapted to fit the corners of the wooden strip 45. The lower sash L is, of course, provided with a holding device, the shoe 15 of which may ride in an arcuate groove 47, milled in the jamb 10', in which a guide pin 14 also rides. The upper sash U, since it is guided between the wooden strip 42 and the blind stop 18 of Fig. 2, does not require guide pins, and the holding device for the upper sash may be provided with a shoe having a flat, rather than a curved surface, merely for pressing against the surface of the jamb 10' between the blind stop 18 and the wooden strip 45. As will be evident, the foam rubber or other non-metallic, resilient material of strip 43 continually presses wooden strip 45 toward the side bars 22' and 23'. However, the wooden strip may move inwardly and outwardly in the groove 44, as between the full position and the dotted position indicated in Fig. 7, the strip 45 being mounted for such movement, as by a series of spaced screws 48, extending through suitable holes 49 in strip 45 and into jamb 10', the head of each screw 48 being disposed in the countersunk end of a hole 49, so that movement of the strip 45 in a direction away from jamb 10' will be limited, yet movement of the strip 45, through compression of the resilient strip 43, may be produced without the head of the screw 48 extending beyond the top surface of the wood strip 45. It will be understood, of course, that other resilient means, such as coil or leaf springs, may be utilized instead of a strip of foam rubber or the like.

The movement upwardly and downwardly of the sashes, when the track T is constructed in the manner illustrated in Figs. 6 and 7, is accomplished in the same manner as when the track T is constructed in other ways, the holding devices H operating in the manner described later. When one of the sashes is to be removed from the frame, the lower sash L may, of course, be removed merely by retracting the shoe 15 of each holding device, to move it out of the groove 47, whereupon the lower sash may be swung outwardly, and then tipped slightly to disengage a pin 14 from the groove 47. However, when the upper sash is to be removed, lateral pressure is exerted on the top bar of the sash, at the same time that the holding device is retracted, the resilient strip 43 on the opposite side of the frame being compressed to an extent that the top of the sash will clear the strip 45 on the uncompressed side, thus permitting the upper sash to be moved outwardly until in substantially horizontal position, whereupon one edge of the sash may be tipped, to disengage the guide pins 19, as described previously.

A further advantage of the stop pins 11 of Fig. 1 lies in the re-introduction of the sashes into the frame. When placing either of the sashes in the frame, one of the guide pins 19, in the case of the upper sash, may be placed in a groove 21, with the adjacent side of the sash resting on one of the stop pins 11. Then, the opposite pin 19 may be placed in the opposite groove 21 and the sash tipped downwardly until both sides rest on the stop pins 11. This aligns the sash in a plane perpendicular to the jambs 10, so that when the sash is then swung upwardly into its final position (the holding device H being retracted during such movement), the sash will slip readily into position. If the sash were twisted, i. e. not disposed in a plane perpendicular to jambs 10, such attempted movement would involve considerable experimental movement of the sash, to obtain proper alignment. Similarly, the lower sash may be accurately and readily inserted in position by placing one of the guide pins 14 in a groove 16, with the adjacent side of the sash resting on a stop pin 11. Then, the opposite guide pin 14 is placed in the opposite groove 16 and the sash moved downwardly until both sides rest on the stop pins 11. Since this aligns the sash in a plane perpendicular to the jambs 10, the sash may be more readily tipped upwardly into final position, the holding devices being retracted during such movement.

The holding device H, illustrated in Figs. 9-13, includes a housing or casing 50 adapted to be inserted in a mortised groove 51 in a side bar 22 or 23 (or 22' or 23') of a sash. The housing 50 is substantially rectangular in shape, being open at the front, top and bottom, and having sides 52 provided at the front edges with laterally extending flanges 53 for which shallow grooves, as in Fig. 9, may be provided in the side bar of the sash. In the back of the housing, a pair of holes 54, disposed adjacent opposite ends, as in Fig. 12, may be provided so that a pair of screws or the like may be utilized in fastening the housing within the groove 51.

The shoe 15, as in Fig. 12, may be generally flat on the rear side and rounded in front, the former to fit against the flat surface of a shoe holder 55, and the latter to correspond generally to the curvature of groove 16 or 21 of the track T. As indicated previously, for use with the track construction shown in Fig. 6, the shoe for the upper sash U may be flat on the outside. The shoe holder 55, as in Figs. 10 and 11, is pivotally attached to the outer end of a link 56, the inner end of which, in the position shown in Fig. 10, bears against a relatively heavy, double bowed spring 57, having a swayback center and arcuate ends, each of the latter resting against the back of the housing 50. In the position shown in Fig. 10, pressure against the shoe 15 will be resisted by spring 57, although sufficient pressure in the direction of dotted arrow 58 will cause the center of the spring to be moved toward the back of the housing, as from the full to the dotted positions of Fig. 10, a slot 59 in side bar 23, as in Fig. 9, accommodating displacement of handle 40. The shoe 15 and shoe holder 55 are normally maintained in an extended position, i. e. with link 56 extending transversely to the center of spring 57, by a tension spring 60, while handle 40, whose inner end extends at 90° extends through slots 61 in the sides 52 of the housing 50. Handle 40 is also provided with a longitudinal slot 62 into which link 56 is adapted to be inserted, the handle and link being locked together by a transverse pin 63 extending through the link and adapted to engage arcuate transverse grooves 64, as in Fig. 12, formed on one side of the handle. As will be evident, the engagement of grooves 64 with link pin 63 also retains the handle in position in the holding device, although the handle is relatively readily inserted or removed, but only when the handle is in an up and down position, such as the full position of Fig. 9. As will be evident from Fig. 11, when the handle is turned, it forms a bearing point for the link on spring 57, and the connection between link pin 63 and handle grooves 64 tends

to prevent the handle from being removed from the sash, since the handle 40 must be moved in the longitudinal direction of link 56 to permit disengagement of pin 63 and grooves 64.

As will also be evident from Fig. 11, when the handle 40 is turned, as from the solid to the dotted position of Fig. 9, the link 56, and the shoe 15 and shoe holder 55 along with it, will pivot from the position of Fig. 10 to the position of Fig. 11. At the same time, the bow spring 57 holds the handle against the ends of the housing slots 61, while the pin 63 prevents the link 56 from sliding through slot 62 in the handle. This pivotal movement of the shoe is, of course, accomplished against the tension of spring 60, and as will be evident, upon release of the handle, the spring 60 will tend to pull the shoe back to the position of Fig. 10. Thus, the shoe is adapted to pivot between the positions of Fig. 10 and Fig. 11, as indicated by the arrows 65 thereof. To prevent the spring 60 from pulling the shoe holder 55 past the center position of Fig. 10, suitable stops may be provided by ears 66, stamped from each side 52 of the housing or casing 50. In addition, a fixed point of attachment for one end of spring 60, on the casing 50, may be provided by prongs 67, also stamped from the side walls 52, at the upper ends thereof, and lapped over, as in Figs. 9 and 12. The opposite end of spring 60 may be attached to the shoe holder 55 at an ear 68, stamped therefrom. A suitable method of constructing the shoe holder 55 will be described later.

During movement of the window sash upwardly and downwardly, certain actions and reactions will occur, primarily involving the relatively heavy bow spring 57 and the considerably lighter tension spring 60. In Fig. 9, the parts are shown as during movement upwardly of the sash, the friction of the shoe 15 in the groove 16 of the track T causing the shoe to pivot slightly downwardly, as shown, while the sash is being moved upwardly in the direction of the arrow 70. As will be observed, the shoe holder 55 and shoe 15 have moved away from the stop at ear 66. As will also be evident, when the upward movement of the sash causes the shoe to pivot downwardly, the full force of bow spring 57 is not exerted against the shoe, but rather will tend to cause the shoe to pivot further. Thus, substantially the only force necessary to raise the window is that required to lift the sash itself, rather than to overcome the friction of wooden guides having a relatively large surface area in contact. As will be observed, the contact between the side walls of the sash and the track is limited to a line of engagement with the relatively resilient central portion 24' of the track, and the inner edge of the arcuate section 31. The friction caused by the shoe 15 and the guide pins 14 riding in the groove 16 will, in general, be negligible. Thus, in distinction to the normally hung sash, with sash weights, cords, pulleys and also additional friction of large areas of wooden surfaces in contact in the channels, a relatively slight upward push is all that is necessary to cause the shoe holder links 56 to pivot. As soon as upward motion of the sash is stopped, the sash will tend to settle downwardly very slightly, which moves the shoe 15 and its holder 55 back against the stop ears 66, and causes the full force of bow spring 57 to be exerted through the link and push the shoe against the track. This will hold the window securely in the desired position.

When it is desired to lower the sash, it is necessary merely to push downwardly on the sash, since the only force to be overcome is the friction of the shoe 15. In general, the force exerted by the bow spring 57 may be predetermined so that the friction produced by the shoe 15 will merely hold the sash in a desired position, and will permit the sash to be moved readily, both upwardly and downwardly. Thus, it is generally unnecessary to touch the handles 40 or 41 of the holding devices H, in moving a window sash upwardly or downwardly, the

use of the handles being necessary only in removing a sash or portion thereof from the track T, as when tilting the lower sash to the non-draft ventilating position of Fig. 1, or in removing either or both sashes for cleaning or similar purposes.

The parts of the holding device H may be made readily, since most of the parts may be stamped from sheet metal, including the casing 50, the shoe holder 55 and the link 56. In forming the casing 50, the screw holes 54 and handle slots 61 may be stamped out at the same time that the blank is formed, while the stop ears 66 and spring attaching prongs 67 may be stamped out in the next operation, in which flanges 53 may also be formed. The blank may then be bent to shape, to form the sides 52. The bow spring 57 and tension spring 60 may, of course, be purchased from a supplier who specializes in the manufacture of springs. The link 56 may be stamped in one operation, which may include the formation of the hole for handle stop pin 63 and ears or pins 71, by which the link 56 is pivotally attached to the shoe holder 55, while the stop pin 63 may then be pressed into the hole therefor. The handle 40 may be formed from round stock, such as brass, being first bent to shape and the slot 61 and grooves 64 sawed or milled before or after bending. In the case of handle 41 of Fig. 2, the handle may be cut to length, the slot 62 and grooves 64 then cut, as by sawing and/or milling, and the slot in the opposite end also cut.

In forming the shoe holder 55, a blank such as shown in Fig. 13 may be first stamped, holes 72, which later form a bearing for the ears 71 of link 56, as well as holes 73, formed at the base of the pointed ends 74, may simultaneously be formed. The side flanges 75, as in Fig. 12, containing holes 72, may then be bent around to a position slightly divergent, so that the flanges may later be pushed together to assemble link 56 and shoe holder 55, with the link ears 71 in holes 72. Also, ear 68 may be punched toward one side, so as to provide a point of attachment for the end of tension spring 69, while central triangular points 76 may be punched to the opposite side. At the same time, or in prior or subsequent operations, the end points 77 may be bent to a position perpendicular to the position of ends 74, which are then bent toward each other, along lines passing through weakening holes 73, such as to the position shown in Fig. 12. The shoe 15, which has been previously cut to length, as from long stock formed by extrusion of the plastic of which the shoe is made, may be placed with the flat side against the shoe holder, being driven onto central points 76, while the ends 74 may be compressed toward each other, so as to drive points 77 into the ends of the shoe, as in Fig. 10. The end points 77 and central points 76 attach the shoe firmly to the shoe holder 55, although other ways of attaching the shoe to the holder, as by cementing, will be evident to those skilled in the art. The mortise in the side of the sash, in which the holder H fits, may be formed by a circular router, since the arcuate ends of the mortise are not visible when the sash is in place, and may form merely a space at each end of the casing 50, which also provides access to the holes 54, through which screws may be threaded into the wood of the sash for attachment purposes.

As indicated previously, a holding device constructed in accordance with U. S. Patent No. 2,521,292, may be utilized, or any other suitable holding device, adapted to maintain the sash in a desired position while permitting upward or downward movement to a desired position.

In the additional alternative side frame element of Figs. 14-16, the jamb 10" is provided with a longitudinal groove 47' for pin 14 of the lower sash and also a similar groove 80 for pin 19 of the upper sash, a non-metallic strip 45', such as wood, being resiliently backed by a series of leaf springs 81, for movement inwardly and

outwardly in longitudinal groove 44' in jamb 10", as to the dotted position of Fig. 14. The strip 45' operates similarly to the strip 45 of Fig. 6, being attached for relative movement to jamb 10" by a series of screws 48, each of which extends through a countersunk hole 49 in strip 45' and also into jamb 10". Strip 45' is pressed outwardly by one or more leaf springs 81, each of which may be attached to strip 45' by a staple 82. Springs 81 are preferably less in number than the total number of screws 48, such as a spring at each end of the strip only, or one spring at the center of the strip, the bow of the spring preferably abutting against the strip 45'. The outer edges of the strip 45' may also be beveled, as shown, and the respective corners of the sash side bars 22" and 23" provided with correspondingly shaped grooves 46', for guiding and sealing purposes. The groove 44' in jamb 10" may also be undercut at one side, as along longitudinal groove 83, which receives the angular lower edge of a longitudinally extending weatherstrip 84, formed of thin, resilient metal. Weatherstrip 84 extends between strip 45' and one side of groove 44', to seal the strip 45' and prevent flow of air therebeneath. As will be evident, the jamb on one side of the window is complementary to the jamb on the opposite side of the window, and the springs 81 press strips 45' against the sashes on each side, but permit a sash to be removed by pressure against one side, which moves the strip 45' on that side inwardly. It will be evident, of course, that coil springs or other types of springs may be substituted for leaf springs 81.

In the additional alternative side frame element of Fig. 17, a jamb face strip 85 and sash bearing strip 86 of generally inverted U-shape may be made of metal, such as aluminum, while a cushion strip 87 may be made of resilient material, such as foam rubber. The jamb face strip 85 may be extruded, while the bearing strip 86 may be formed by rolling, preferably being made of spring aluminum or other suitable metal. The jamb face strip 85 may be attached to the wooden jamb (not shown) of the window frame by screws in countersunk holes of an outer flange 88 thereof overlapping the inner corner of a wooden jamb and the opposite edge extending into a slot in the blind stop (see blind stop 18 of Fig. 6). The jamb face strip 85 may be provided with longitudinally extending, inverted arcuate sections 89, providing grooves for the pins and holding devices of the sashes, and also provided, on opposite sides of a central land 90, with inwardly extending, open top boxes 91 which form longitudinal recesses. A lip 92, extending toward the land 90, is preferably provided at the outer edge of each box 91, to provide stops for flanges 93 of bearing strip 86, extending laterally from the lower edges, it being noted that strip 86 is generally U-shaped in section. Strip 86 may be placed in position by pressing the sides toward each other, so that flanges 93 will clear lips 92, the former springing out to the full position beneath lips 92 when the pressure is removed. Or, the strip 86 may be slid into position from the end, prior to mounting strip 85 in the window. Foam rubber strip 87 may merely lie between land 90 and strip 86, or may be cemented to either. The wooden window jamb may be provided with longitudinal grooves to accommodate sections 89 and boxes 91, or the jamb strip 85 may be mounted on an unfinished wood piece, such as a 2 x 4, provided with filler strips to provide a solid backing beneath land 90 and at each side of grooves 89. Or, the strip 85 may be used alone as the jamb, particularly when installed in a brick or similar wall, with a wooden blind stop or a metal trim strip provided with a groove to receive the outer edge of strip 85. As will be evident, the foam rubber cushion 87 presses a strip 86 out against the sashes, but permits removal of a sash, in a manner similar to that previously described, by lateral compression pressure, such as to move the strip 86 to the dotted position of Fig. 18. The corners of the side bars

of the window sash are preferably grooved to fit against the corners of strip 86, as described previously in connection with Figs. 6 and 14.

From the foregoing, it will be evident that this invention fulfills to a marked degree the requirements and objects hereinbefore set forth. As indicated previously, the track T, in combination with a holding device and the guide pins, adequately guides each sash for upward and downward movement. Also, the resilient engagement of the track with the sash, i. e. when the track strip or strips are made of metal, as in Figs. 3-5, or when the track includes a wood strip mounted on a non-metallic resilient strip, such as foam rubber, as in Figs. 6 and 7; or when the track includes a wood strip pressed outwardly by springs, as in Figs. 14-16, or when the track includes a metal strip pressed outwardly by a non-metallic resilient strip, such as foam rubber, as in Figs. 17 and 18; insures that an adequate seal along the sides of each sash will be obtained. The friction of the shoe or shoes, either in a groove of the track or against the jamb, as in the case of the upper sash in the construction illustrated in Fig. 6, maintains each sash in any desired position, thus eliminating the necessity for sash weights and the like, but at the same time permits the sashes to be moved upwardly and downwardly with relatively little effort. The retraction of the shoes of the holding devices permits either or both sashes to be removed readily from the window frame, such removal being facilitated by the resiliency of the track.

Although alternative constructions of the track have been illustrated and described, it will be understood that other constructions may exist. Thus, embodiments of this invention other than those described and illustrated may exist, and other variations may be made, all without departing from the spirit and scope of this invention.

What is claimed is:

1. In a window construction, an upper and a lower sash; a frame having sides between which said sashes are movable; a longitudinal strip having corners and mounted on each frame side; resilient means for urging said strips outwardly from said frame sides toward said sashes; means for mounting said strips on said frame sides and permitting movement of the respective strip between positions of compression and substantially non-compression of said resilient means; and each said sash having a groove along each edge adjacent each strip, said groove receiving the corners of said strips.

2. In a window construction, an upper and a lower sash; a frame having sides between which said sashes are movable, each frame side having a groove extending longitudinally thereof; a longitudinal strip at least partially in each said groove; resilient means for urging said strips outwardly from said groove; means for attaching said strips to said frame sides and permitting movement of the respective strip between positions of compression and substantially non-compression of said resilient means; and each said sash having a groove along each edge adjacent each strip, said groove receiving the corners of said strips.

3. In a window construction, an upper and a lower sash; a frame having sides between which said sashes are movable, each frame side including a longitudinally extending, metallic strip having a pair of grooves extending longitudinally thereof in laterally spaced relation, and an inverted box-like groove extending longitudinally at each side of a centrally disposed, flat land, each said box-like groove having a lip extending toward said central land from the opposite side thereof; a flat strip of resilient, non-metallic material on each said land; an inverted U-shaped strip of metallic material resting on said resilient strip and having laterally extending flanges received in said box-like grooves beneath said lips, for movement between positions of compression and substantially non-compression of said resilient strip; and each said sash having a groove along each edge adjacent

11

each inverted U-shaped strip, said grooves receiving the corners of said strips.

4. In a window construction including a frame having sides between which a sash is movable, a track for said sash and extending along at least one of said frame sides, said frame side having a longitudinal groove to receive said track and said track including means defining a longitudinally extending, central land and a longitudinal recess at each side of said land, with a lip extending inwardly from the edge of each recess opposite said land; a metallic strip extending longitudinally and having a generally inverted U-shape with corners at the base thereof and an outwardly extending flange at each side and spaced from said corners, said flanges being received in said recesses and engaging said lips to limit movement of said strip away from said land; and resilient means for urging said strip away from said land.

5. In a window construction as defined in claim 4, wherein said sash is provided with a groove along one edge engaging at least one corner of said strip.

6. In a window construction including a frame having sides between which a sash is movable, a track for said sash and extending along at least one of said frame sides, said track including a longitudinal strip mounted on said frame side and providing at least one corner; resilient means for urging said strip toward said sash; means mounting said strip on said frame side for limiting movement of said strip by said resilient means; and said sash having a groove along one edge receiving the corner of said strip.

30

12

7. In a window construction as defined in claim 6, wherein said longitudinal strip is non-resilient; said frame side is provided with a longitudinal groove; and said resilient means is disposed in said groove.

8. In a window construction as defined in claim 7, wherein said resilient means comprises at least one spring.

9. In a window construction as defined in claim 8, wherein said spring comprises a bow spring having its ends engaging the bottom of said groove and its center attached to said strip.

10. In a window construction as defined in claim 7, wherein said resilient means comprises a non-metallic resilient strip in said groove.

11. In a window construction as defined in claim 7, wherein said means mounting said strip on said side frame includes a series of screws having heads and extending through said strip at spaced positions therealong, said strip having holes therethrough for said screws and said holes being countersunk to accommodate the heads of said screws.
